UNITED STATES PATENT OFFICE.

JAMES WILSON, OF ST. LOUIS, MISSOURI.

HEATING-STOVE.

SPECIFICATION forming part of Letters Patent No. 532,855, dated January 22, 1895.

Application filed October 29, 1894. Serial No. 527,197. (No model.)

To all whom it may concern:

Be it known that I, JAMES WILSON, of the city of St. Louis and State of Missouri, have invented certain new and useful Improvements in Heating-Stoves, of which the following is a full, clear, and exact description, reference being had to the accompanying drawings, forming a part hereof.

My invention relates to heating stoves, the object of my invention being to construct a stove preferably of sheet metal, said stove having double side-walls and the draft-flue thereof on the inside of the stove and between the two walls.

My invention consists in certain novel features of construction, combination and arrangement of parts, hereinafter described and claimed.

In the drawings: Figure 1 is a side elevation of my improved stove. Fig. 2 is a top plan view thereof. Fig. 3 is a longitudinal sectional view taken approximately on the line 3—3 of Fig. 2. Fig. 4 is a top plan view of the damper of which I make use in the construction of my stove. Fig. 5 is a bottom perspective view of one end of said damper. Fig. 6 is a horizontal sectional view taken approximately on the indicated line 6—6 of Fig. 3.

Referring by numerals to the accompanying drawings, 1, 1 indicate ordinary stove-legs, the same being fixed in any suitable manner to the bottom-plate 2, said plate having in the center thereof a rectangular opening 3. Located immediately beneath this opening 3 and adapted to slide backward and forward in bearings 4 fixed to the under side of the bottom-plate 2 is an ash-pan 5.

Mounted upon the bottom-plate 2 and fixed in any suitable manner to the flange 6 on the edge of said plate is the outer wall 7 of my stove, the same being oval in plan view. This wall is preferably constructed of sheet metal, and has fixed to the upper edges the top-plate 8, said top-plate 8 having near one end thereof a circular opening 9, the same adapted to be closed by a suitable cover, such as 10. Near the other end of the top-plate 8 is a circular opening 11, the same being surrounded by an annular collar 12 upon which the stove-pipe 13 is adapted to be mounted.

Rigidly fixed to the bottom-plate 2 and the top-plate 8 and within the outer wall or cas-

ing 7 is the inner wall 13, the same being formed of sheet metal, or any suitable material, oval in plan view to conform with the outer wall of the stove, and of such a size as to leave a slight air space 14 between it and the outer wall 7. At one end of and near the lower edge of the inner wall 13 is formed a transverse slit 15. The material above this slit 15 is then bent into semi-circular form, as indicated by 16 (Fig. 6), thus forming the draft-flue 17. Immediately above this draft-flue and in the top-plate 8 of the stove are formed draft-openings 18 that are adapted to be closed by a sliding cover 19, the same having openings 20 therein adapted to register whenever desired with the draft-openings 18.

A sliding cover for the opening 3 that leads into the ash-pan 5 is formed of a rectangular piece of sheet metal 21, the same having riveted to the under side thereof a strap 22, the ends of which are bent into a plane below the body thereof in order that they will engage beneath the edges of the rectangular opening 3, thus forming a guide for said sliding cover 21.

The handle 23 is fixed in any suitable manner to the top side of the sliding cover 21 and extends horizontally through the double wall 8 of the stove, and is there provided with a ring or handle 24. By this handle the sliding cover is manipulated.

In the practical operation of my improved stove, fuel having been placed upon the bottom-plate 2 thereof and lighted, the products of combustion will pass out through the circular opening 11 and up through the stove-pipe to the chimney. The sliding cover 19 being manipulated so that the draft openings 20 therein register with the draft openings 18 in the top-plate 8, cold air will pass through said openings and downward through the draft-flue 17 formed between the double wall of the stove. As said air passes downwardly through said draft-flue, it will necessarily to some extent become heated and in this state will pass into and be consumed by the flame. This I have found produces much better combustion than where cold air is introduced directly into a fire; also the heating powers of a fire of this character are greatly increased.

When desired, the handle 23 is pulled out

ward, thus uncovering the ash-pan 5 and permitting the ashes to fall into said ash-pan, and from there to be removed.

Thus it will be seen how I have constructed 5 a stove that may be produced at minimum cost, and that possesses superior advantages in point of simplicity, durability and general efficiency.

What I claim is—

10 1. A heating stove constructed with double walls, and a down-draft flue stamped or bent from the inner one of the double walls.

2. A heating-stove constructed with double walls, a down-draft flue formed between the 15 walls of said stove by forming a horizontal slit near the lower edge of the inner wall and

bending or stamping the material above said slit into semi-circular form.

3. In a heating-stove, the combination of a top and bottom plate, an outer wall, and an 20 inner wall, the same being constructed to conform with the outer wall and provided with a vertical inwardly bent portion which forms the down-draft flue between the two walls of the stove.

25 In testimony whereof I affix my signature in presence of two witnesses.

JAMES WILSON.
